ATTORNEYS.

UNITED STATES PATENT OFFICE.

CHARLES S. MURLLESS, OF HOLYOKE, MASSACHUSETTS.

DESIGN FOR A DENTIST AND SURGEON CABINET.

56,622.

Specification for Design.

Patented Nov. 16, 1920.

Application filed December 15, 1919. Serial No. 345,138. Term of patent 7 years.

To all whom it may concern:

Be it known that I, CHARLES S. MURLLESS, a citizen of the United States, residing at Holyoke, in the county of Hampden and State of Massachusetts, have invented a new, original, and ornamental Design for a Dentist and Surgeon Cabinet, of which the following is a specification, reference being had to the accompanying drawing, forming a part thereof.

I claim—

The ornamental design for a dentist and surgeon cabinet as shown.

CHAS. S. MURLLESS.
